UNITED STATES PATENT OFFICE.

THEODORE W. MUCKLE, OF DENVER, COLORADO, ASSIGNOR TO WILLIS W. CASE, JR., OF DENVER, COLORADO.

FURNACE PART.

1,172,223.

Specification of Letters Patent.

Patented Feb. 15, 1916.

Original application filed June 1, 1915, Serial No. 31,500. Divided and this application filed August 16, 1915. Serial No. 45,794.

To all whom it may concern:

Be it known that I, THEODORE W. MUCKLE, a citizen of the United States, residing in the city and county of Denver and State of Colorado, have invented certain new and useful Improvements in Furnace Parts; and I do hereby declare the following to be a full, clear, and exact description of the invention, such as will enable others skilled in the art to which it appertains to make and use the same.

This invention relates to improvements in furnace parts, and while the same may be used with other types of furnaces, it is more particularly applicable to assay furnaces, in which a liquid fuel is forced into the combustion chamber of the furnace.

The invention being divided out of my former application for metallurgical furnaces and furnace parts, #31,500, filed June 1, 1915, the same will be described with reference to a metallurgical furnace of the muffle type.

In muffle furnaces, heated by gas or hydro-carbon fuel, it frequently occurs that, upon initial ignition the compression and impact of the combustible fluid is so great, the muffle is either broken or is blown from its seat, causing the contents of the ore containing vessels therein to become spilled.

The primary object of the present invention, therefore, is to overcome this disadvantageous feature, by providing means, whereby a substantial opening to the atmosphere may be created upon initially firing the furnace, which opening may be closed after the furnace is started, and which opening is located at the front of the furnace and permits of the inspection of the combustion chamber and regulation of the burner at the same time, and also provides means for inserting a lighted torch into the combustion chamber for purposes of ignition.

With these ends in view, the invention consists in the novel elements of construction and arrangement of parts as will be more fully described in the specification and particularly pointed out in the appended claims.

While the invention is not restricted to the exact details shown and described, still, for the purpose of more fully understanding

the same, reference is had to the accompanying drawings, illustrating a practical embodiment of the same, in which drawings like characters designate the same parts in the several views, and in which:—

Figure 1, is a longitudinal sectional view through the furnace, the burner boss being partly broken away, and the burner and fan blower connections being shown in elevation. Fig. 2 is a fragmentary sectional view of the front of the furnace, the burner being shown in elevation, and a section of the burner boss being shown in dotted lines, illustrating its removability. Fig. 3, is a side elevational detail view of the burner boss, with its parts shown in closed relation. Fig. 4, is a similar view in front elevation, and Fig. 5, is a view in vertical section, taken along the line 6—6 of Fig. 4.

I will now briefly refer to various parts of the furnace illustrated, although they form no essential part of the present invention.

1 designates a hollow sectional furnace body of fire clay, having a forward opening or door 2, the upper portion of the furnace body providing the muffle chamber 3, and the lower portion providing the combustion chamber 4.

5, is the muffle provided with a tubular projection 6, located below a flue 7, having a damper 8, the whole coöperating to create a suction or ejector force through said tubular projection to facilitate the discharge of fumes and gases from said muffle.

9 is another flue having a damper 10, and both flues open into the muffle chamber.

11 is a shelf at the forward opening or door of the muffle chamber, and 12 is an iron sheathing incasing the furnace, the furnace being supported on a suitable stand 95 or framework 13.

14 designates a liquid fuel burner, of a preferred type, 15 the oil pipe leading thereto, and 16 the air or blast pipe connected to the burner and to the fan blower 17.

It will be noted that in the front wall of the furnace, and preferably centrally thereof, I provide a burner opening 18, and the location of the burner opening is important, as it enables the operator to control the burner, while inspecting the contents of the muffle or the interior of the combustion chamber, instead of having to go around to

the rear of the furnace to regulate the burner, where the burner opening has heretofore been located, and where he cannot inspect the contents of the furnace.

5 The burner opening also admits of another important advantage, which will now be referred to, and which is the essence of the present invention.

10 The furnace, adjacent the burner opening, is provided with a furnace part, consisting of a movable closure, which may be opened when the furnace is started to admit of igniting the combustible charge, but more important still, to provide a substantial 15 opening to the atmosphere from the combustion chamber, the burner opening being of much greater diameter than the nozzle of the burner, which is spaced therefrom. This opening to the atmosphere relieves the compression within the combustion chamber 20 upon initially igniting the charge, a desirable feature, as it has been found that this compression and the impact of the flame, frequently blows the muffle from its seat, 25 spilling the contents of the ore containing vessels in the muffle, or breaks the muffle itself, as hereinbefore mentioned. This movable closure also permits of the inspection 30 of the combustion chamber and the condition or extent of combustion therein, even while the burner is being regulated. It forms no special feature of the burner, however, but is a part of the furnace itself, and co-operates therewith more particularly than 35 with the burner. I wish to state, however, that I do not limit myself to the particular form of this closure as shown, for it may be variously designed, and made in one or more parts of iron, fire clay or other suitable substance; but in the drawings I have 40 illustrated a practical segmental form of a burner boss, which is designated at 19 as being of conical structure.

45 The lower section 20 is shown with a flange 21, which is bolted to the sheathing 12, and the upper section 22 may have tongues or ribs 23, adapted to fit into grooves 24, formed in the lower section, to prevent accidental displacement of the members 50 when assembled. The upper or movable section may also be provided with a lip or lug 25, to enable a rod or wire to be hooked into the apertured lug for lifting up said movable closure and replacing the same on 55 the stationary closure. Thus it will be seen more clearly from Figs. 1 and 2 that, when the closure 22 is removed, a substantial opening 26 is provided at the upper portion of the burner opening to relieve the compression 60 in the combustion chamber, and after the furnace is fired this cover is replaced during further operations. It may also be

removed for inspecting the condition or extent of combustion in the combustion chamber.

65 In Fig. 1, 27 designates a plurality of offset pedestals for supporting a muffle plate 28, which in turn provides a fire clay division plate between the muffle and combustion chambers, and directly supports the 70 muffle. I consider this an important feature as it takes the shock off of the muffle, but as the same is specifically referred to and claimed in my former application mentioned, it is believed that further description 75 in the present application is unnecessary.

It is also believed that, in view of the drawings and the foregoing complete statement of the function of my improvements, further description of same and the mode 80 of operating would be unnecessary and superfluous, and

Having thus described my invention, what I claim is:—

85 1. In a metallurgical or similar furnace, having a combustion chamber and a burner opening leading thereto, a hollow separable boss member communicating with said burner opening, comprising upper and lower portions, the lower portion of said 90 boss member being fixed and the upper portion being removably seated on said lower portion to directly open and close a large portion of said burner opening to the atmosphere, and a burner for said burner 95 opening.

100 2. In a metallurgical or similar furnace having a combustion chamber and a burner opening leading thereto, a burner adjacent said opening, and a two part boss member interposed between said burner opening and said burner, forming an open continuation therebetween, the lower portion of said boss being fixed and the upper portion being removably seated on said lower portion to 105 open and close a large portion of said burner opening to the atmosphere as desired.

110 3. In a metallurgical or similar furnace having a combustion chamber and a burner opening leading thereto, a burner adjacent said opening, having a nozzle of substantially lesser diameter than said burner opening, and a two-part boss member interposed between said burner opening and burner, forming a conical continuation therebetween, the lower portion of said boss being fixed and the upper portion being removably seated on said lower portion to open and close the upper portion of said burner opening to the atmosphere as desired.

115 In testimony whereof, I affix my signature.

THEODORE W. MUCKLE.
